LAST AND LAST-MAKING.

1,352,518.

Specification of Letters Patent. Patented Sept. 14, 1920.

Application filed July 14, 1916. Serial No. 109,315.

To all whom it may concern:

Be it known that I, PAUL F. W. C. KRIPPENDORF, a citizen of the United States, residing at Lynn, in the county of Essex and State of Massachusetts, have invented certain Improvements in Lasts and Last-Making, of which the following description, in connection with the accompanying drawings, is a specification, like reference characters on the drawings indicating like parts in the several figures.

This invention relates to the manufacture of shoes, and comprises novel apparatus for such manufacture, and novel machinery for the production of such apparatus.

Lasts now used in the manufacture of shoes are turned on copying lathes having two "graders" or pantographic reproducing mechanisms. A single model may be used for the whole set of lasts, the length grader magnifying or reducing all their dimensions parallel to the axis of rotation of the model, and the width grader magnifying or reducing all its dimensions perpendicular to this axis. The magnifications and reductions are, in general, proportional in different parts of the last, *i. e.*, all dimensions parallel or perpendicular, respectively, to the axis of rotation are altered by the same percentage of themselves. The two graders are entirely independent in this action.

In the simplest practice of turning a set of lasts the graders are so adjusted that "a set of graded lengths", that is, a series of lasts all having the same width number, are substantially geometrically similar solids varying in absolute length by $\frac{1}{2}$ inch for each unit in the size (*i. e.* the length) number; while their perimeters at the ball, waist and instep vary by $\frac{1}{4}$ inch for each unit in the size number. On the other hand, "a set of graded widths", that is, a series of lasts all having the same size (or length) number, have their lengths the same, and their corresponding cross-sections taken perpendicular to their axes of rotation in the lathe, are geometrically similar plane figures, varying in perimeter at the ball, waist and instep by $\frac{1}{4}$ inch per unit of the width number.

In mechanical terms, if a set of lasts are to be turned from a 4B model, the graders when set at zero will reproduce the model. When both graders are set "one size up"

they will produce a 5B, when both are set two sizes up they will produce a 6B. If 55 7D is desired, the length grader is set up three sizes and the width grader five sizes; three sizes to produce the 7B and two more to produce the 7D.

I have observed that shoes of extreme widths graded according to the above described practice often fail to fit properly. That practice of grading increases the lateral thickness of the heel bottom less in 65 successive widths than that of the tread face at the ball, since the heel bottom is narrower than the tread face at the ball, and each dimension is increased by 70 the same percentage of itself. I have observed that short wide feet are often broader at the heel than the lasts which are thus graded, with the result that the shoe counter is broken down around the edge of the heel seat, and the shape of the shoe is 75 spoiled. The uneven distribution of the material "graded on" to the model in other parts of the shoe also unfavorably affects the fit of the shoe. An analogous difficulty is found in the case of certain types of long 80 narrow feet.

It is an important object of my invention to obviate this difficulty by providing a set of lasts having novel dimensional relations to one another, upon which shoes may be 85 made which will fit certain types of short broad feet or long narrow feet better than shoes heretofore provided, and to provide mechanism for the manufacture and in particular, the grading of such lasts.

Another phase of the difficulty arising from this unequal distribution of the "graded on" material is the exaggerated toe springs of the wide lasts. Much, and in many styles of lasts, nearly or quite all, 95 of the graded on material at the ball is placed on the bottom. This increases the toe springs of the wide lasts rapidly and brings them badly out of correspondence with the foot. It is a further object of my 100 invention to provide lasts which shall not be subject to this difficulty.

In actual practice the turning and grading of a set of lasts is not as simple as above described. Shoe manufacturers and retailers insist that departures from the above practice be made in the cases of the lasts wider and narrower than the model size for 105

the sake of psychological impression on the customer. The practice of one such departure from the simpler practice is much simplified by my invention. This relates 5 to the "extensions" of the wide lasts. If a 4B model is graded out to a 4EE, the increase in lateral dimensions, accompanied by no increase in longitudinal dimensions, will change the appearance of the shoe to such 10 extent that the customer cannot be convinced that it is the same style shoe exhibited in the store window. It is often the custom, therefore, to increase the lengths of the wider lasts of the same length number 15 by perhaps $\frac{1}{2}$ inch ($\frac{1}{4}$ size) for each unit of increase in the width number, and, though perhaps less frequently, to decrease the lengths of the narrower lasts of the same length number, in the same way. The manipulation of the length grader necessitated 20 by this practice is quite complicated and subject to error. It will be seen that my invention provides for these "extensions" in a very simple manner.

25 A feature of my invention is a novel organization of a model wheel and cutter of different diameters, whereby a last may be cut from a model differing by a layer of uniform thickness from a last graded regularly from the model.

Another feature of my invention is a last 30 lathe having a cutter and model wheel of different effective diameters. The swing frame is thus held constantly at an "offset" 35 from the position which would be given it in the ordinary lathe whereby a film of material of substantially uniform thickness is graded on or off the model, independent of the action of the width grader.

40 Another feature of my invention is a last lathe in which the point of finishing contact of the cutter and block in certain parts of the work is maintained proportionally farther from the axis of rotation of the block 45 in the wider lasts than in the narrower.

Another feature is a last lathe having a model wheel and cutter the effective surface of one of which is equivalent to that of the other plus a filler of uniform thickness.

50 Another feature of my invention is a combined model wheel and width grader having a fixed operative position. This obviates the cramping and lost motion which always cause more or less difficulty in the use of the 55 many jointed width grading mechanism heretofore used.

Other features of the invention, including certain details of construction and combinations of parts, will now be described in 60 connection with the accompanying drawings, and the invention will then be pointed out more definitely in the claims.

In the drawings, which illustrate the preferred manner of practising my invention,

Figure 1 is a fragmentary plan view of a 65 last lathe in which my invention has been embodied, showing diagrammatically the principal working parts of the lathe.

Figs. 2, 3 and 4 are details showing the improved combined model wheel and width 70 grader provided by my invention,

Figs. 5 and 6 show the distribution of material "graded on" a model by the ordinary pantographic width grader,

Figs. 7, 8 and 9 illustrate my preferred 75 solution of the width grading problem, and Fig. 10 illustrates an alternative practice.

Fig. 5 shows in full lines a sectional outline of a model last at the instep, and in dotted lines the corresponding outline of a 80 wider last graded from the model by means of the ordinary width grader. The sections have been similarly oriented and placed with their centers of rotation in the lathe in coincidence at 10, so that the distribution of 85 the material 11 graded on to the model is shown. The different radii vectores of points on the model surface are all increased by the same percentage of their own length in order to form the surface of the wider 90 last. Fig. 6 shows a corresponding longitudinal vertical sectional outline of a model and a wider last, without "extension" the sections being arranged with their axes in coincidence. The radii vectores of the model 95 surface are, as before, all multiplied by the same factors to form the surface of the wider last.

The surplus material or filler 11, which may be regarded as added to the model to 100 produce the wider last, is distributed mainly upon the sides and top of the last at the instep and heel, and upon the bottom at the ball. The increase in lateral thickness is less at the heel than in other parts of the last. 105

I have observed that shoes which are width graded in this way fail to fit properly in many instances. I have found that short broad feet frequently have substantially the same sized skeleton as narrower feet of the 110 same length, the difference being only in the varying amounts of flesh carried on the skeleton in different individuals. This excess or deficiency of flesh over or under the average or model size I have observed to 115 occur with substantial uniformity all over the foot. It is therefore clear that shoes width graded as shown in Figs. 5 and 6 will fail to fit properly feet of this type. My invention removes this difficulty. 120

Figs. 7 and 8 are sectional outlines similar to those shown in Figs. 5 and 6 except that the material 12 added to the model for the wider last is added in equal thickness at all points of the surface. Lasts width 125 graded in this manner will correspond better to feet of the type I have described than those graded according to the pantographic

practice, since they provide for a uniform accumulation of flesh upon a skeleton of the average size.

I will describe my novel machinery for
5 grading lasts in this way.

Fig. 1 shows diagrammatically the model centers 13, and the block centers 14, which are a portion of the well known swing frame mechanism, the model wheel carriage 15, the cutter carriage 16, the length grader and connecting mechanism 17, the model wheel holder 18 and the fan board width grader 19, all of the well known construction which has been in use more than twenty years, and no further description of them is thought necessary.

The model wheel of the lathe is of peculiar construction, see Figs. 2, 3 and 4. It comprises a central spider 20 which may be mounted upon the model wheel axis 21 of any standard last lathe, instead of the model wheel supplied with the lathe. The circumferential face 22 of the spider is coned so that any one of a series of rims 23 can be applied to it, and fastened with screws as shown, or in any convenient manner. The external or working surfaces of these rims have a progressive relation which may be defined as follows:

30 The surface of revolution generated by the finishing edge of the cutter as it revolves, may be called the "effective surface of the cutter." It is indicated in dotted lines in Fig. 2. One rim 24 is provided having exactly such an external surface. When this rim is placed on the spider, and a model and block placed in the lathe in the ordinary manner, and the graders set at zero, a last will be turned which will be a duplicate of the model. In fact, the lathe thus equipped is the exact equivalent of the ordinary lathe.

A second rim 25 is provided, having an effective surface equivalent to that produced by adding outside of the effective surface of the cutter or outside of the effective surface of the first rim a filler of uniform thickness of about $1/25$ inch. When this rim is mounted on the spider, the lathe being otherwise adjusted as before, a last having the relation to the model that the dotted line outline bears to the full line outline in Figs. 7 and 8 will be produced. This will be clear from an examination of Fig. 8 in which the model, block, model wheel and cutter may be regarded as superposed, with their respective axes of rotation in coincidence. The model 26 and the effective surface 27 of the model wheel are represented in full lines, and the last 28 being cut and the effective surface of the cutter 29 in dotted lines. It will be seen that the surface of the last is equidistant from the corresponding part of the surface of the model at all points, or in other words, that the last is equivalent to the model plus a "plating" or "filler" $1/25$

inch thick all over its surface, and that the perimeters of its sections perpendicular to the axis of revolution will all differ from those of the corresponding sections of the model by approximately $\frac{1}{4}$ inch.

($2\pi \cdot 1/25 = \frac{1}{4}$ approximately.)

This filler is added at the ends of the last as well as on its sides, as shown. The length of the last is therefore increased over that of the model by $2/25$ inch, which is nearly $\frac{1}{4}$ of a size. The matter of "extending" the wide lasts is therefore taken care of in my novel machine without special adjustment. In case it is not desired to extend the wide lasts, the length grader can be adjusted to compensate for this $2/25$ inch increase in length. 75 80

My invention contemplates the provision of a series of rims each differing from the next member of the series by a "plating" or "filler" on its effective surface corresponding to the change in perimeter of the last

desired per unit change in width number, whereby a series of lasts may be produced each having such relations to adjacent members of the series as are shown in Fig. 8. It will be clear also, that though I have described and shown how to grade lasts wider than the model, my invention also contemplates grading narrower than the model in the same way. The "cutter size" rim may be an intermediate one of the series, and the apparatus may be used to grade up or down. The smaller rims will be formed by subtracting a film of uniform thickness from the effective surfaces of the rims.

the effective surfaces of the rims next larger. Fig. 9 illustrates this grading of a last narrower than the model. As in Fig. 8, the surface of the model 26 and model wheel 27 are represented in full lines, and the surface of the last 28 and effective surface of the cutter 29 are represented in dotted lines. So far I have described only the cutting of lasts of the same size number as the model. I do not believe it necessary to alter the relations existing under the present practice between lasts of the same width number, whereby such lasts are substantially geometrically similar solids, their lateral dimensional relationships being as shown in Fig. 5. My invention, however, in its broadest aspects, contemplates the application of the principles discussed to lasts of varying length numbers, if such application should prove to be advisable, and it is of course plain that I may apply the layer of uniform thickness upon a last graded in the ordinary way, so that the last produced is the result of a combination of the old and new functions. That is, a 4E may be produced from a 4B model by setting of the width grader two sizes, putting on the model wheel the rim corresponding to a grade of one size up, or by grading up 4 130

sizes on the width grader and down one size by means of the proper rim. The "uniform thickness" of the layer may thus be positive or negative. At present, however, I con-
 5 template turning all the B width lasts, from (say) a 4B model, by setting the length and width graders one size each up or down as the case may be, for each unit change in the length number, and mounting the "cut-
 10 ter size" rim on the spider. The wider and narrower lasts of the same length numbers will be cut by interchanging the rims as de-
 scribed, leaving the other adjustments un-
 15 changed. The lasts having the same width number will be substantially geometrically similar solids and the dimensions of one may be obtained from the corresponding dimensions of another through multiplication by a constant. The series of lasts having
 20 the same length number will have the same or slightly varying lengths while trans-
 versely they sustain with one another an arithmetical relationship, *i. e.* one of simple addition or subtraction of a constant. I in-
 25 tend, however, that the term "width grad-
 ing" or similar words, in the appended claims shall be construed broadly enough to cover the production of lasts having lateral dimensions different from the lateral dimensions of the model, regardless of the
 30 length number.

The fanboard width grader has so many links and joints and disadvantageous leverages that it gives considerable trouble as
 35 soon as it is slightly worn, and my invention provides means for grading widths of the same length as the model with no moving parts of this kind. A set of models of (say) B width may be provided, and the whole
 40 set of lasts may be cut from them without the use of the fanboard at all, the axis of the model wheel remaining motionless. An ex-
 ceedingly positive and infallible operation of the lathe is thus secured.

45 My invention has another remarkable advantage. Fig. 6 shows that the axis of rotation of the last in the lathe comes very close to the upper surface of the last at the ball portion, or even above it, in lasts of some
 50 styles, such as the one shown. The present practice of width grading, as described, accord-
 ingly grades on the greater part of the material added at the ball portion to form the wide lasts, at the bottom. The tip of the
 55 toe is on the axis, and the position of that point is unaltered. As a result the "toe spring", or distance 30 in Fig. 6 increases rapidly in the wide lasts, bringing them correspondingly out of proper relation to the
 60 feet they are to fit. The practice of my invention, as shown, cuts this difficulty sub-
 stantially in half, owing to the uniform dis-
 tribution of the material added, the toe
 springs of the wide lasts increasing only

half as rapidly as under the old practice. 65 See Fig. 8.

I have shown in Fig. 10 an alternate practice in the grading of widths. In grading a last wider than the model according to this practice the adjustable connection between 70 the model wheel axis 21 and the fan board 19, which is found in all standard lathes, is lengthened $1/25$ inch, the effective surfaces of the cutter and model wheel remaining identical. This has the effect of keeping 75 the swing frame out $1/25$ inch farther at all times than it would normally be, and, as shown in Fig. 10, reproduces points in the model surface $1/25$ inch farther from the axis of rotation than would have been done 80 normally, while the procedure shown in Figs. 8 and 9 reproduces each point of the model surface $1/25$ inch distant from the surface of the model, *i. e.* along a normal to the surface. The filler of Fig. 8 is of uniform 85 thickness; that of Fig. 10 is of uniform height. The procedure illustrated in Fig. 10 does not "extend" the wider lasts.

Lasts graded according to the principles illustrated in Figs. 7, 8, 9 and 10 may 90 be said to have their smaller dimensions graded more rapidly than their larger dimensions, since the constant lateral dimension of $1/25$ inch of the "graded on" material is a larger proportion of the smaller 95 dimensions of the last than of the larger.

Having described by invention, what I claim as new and desire to secure by Letters Patent of the United States is:

1. A last lathe having work and model ro-
 tating means, a rotating cutter and a model
 wheel, the diameter of said wheel being dif-
 ferent from that of said cutter and the axes
 of rotation of the cutter and wheel being
 100 equidistant from those of the work and
 model, respectively, the machine being thus
 adapted to cut a last differing from the model
 by a layer of uniform thickness.

2. A last lathe having a cutter and a model
 wheel, the principal radii of curvature of 110
 the effective surface of the wheel differing
 by constant amounts from the corresponding
 radii of curvature of the effective surface of
 the cutter.

3. A last lathe having swing mechanism 115
 for carrying a model and block, and a rotat-
 ing cutter and a model wheel, the axes of
 rotation of which have identical relations to
 those of the block and the model, respec-
 tively, the diameter of said wheel being dif-
 ferent from that of said cutter.

4. In a last lathe, swing mechanism con-
 structed to carry a model and a block, and
 a cutter and a model wheel the effective sur-
 face of one of which is equivalent to that of 125
 the other plus a filler of uniform thickness.

5. In a last lathe, a model wheel, a cutter,
 grading mechanism and swing mechanism

arranged to carry a model and a block, all constructed and arranged to maintain the point of finishing contact of the cutter and block at a uniform distance from the surface 5 of an ordinarily graded last in said block.

6. In a last lathe, a cutter, swing mechanism adapted to carry a model and a block, and width grading mechanism in relation to said model, constructed and arranged to 10 swing said swing mechanism proportionately farther in some parts of the cutting than in others to produce a last equivalent in form to a pantographically graded last from the same model plus a layer of uniform 15 thickness.

7. In a last lathe, a cutter, width-grading mechanism, mechanism for holding a model and block and presenting them to said grading mechanism and cutter, respectively, said 20 grading mechanism being constructed and arranged to produce lasts of progressively varying widths from the same model, and to grade more rapidly in some portions of the lasts than in others whereby a last is 25 produced equivalent to a pantographically graded last plus a layer of uniform thickness.

8. In a last lathe, a cutter, width grading mechanism, swing mechanism for holding 30 and presenting a block and a model to the mechanism and cutter respectively, constructed and arranged to maintain the point of finishing contact of the cutter and block on a surface having radii of curvature con- 35 stantly differing from the corresponding radii of curvature of the surface of an ordinarily graded last within said block.

9. In a last lathe, a swing mechanism for carrying a model and a block, a cutter ar- 40 ranged to operate on said block, and grading mechanism constructed and arranged to impress upon said swing mechanism simultaneous grading movements dependent on and independent of the dimensions of that part 45 of the last being cut whereby the surface of the last cut is placed at a uniform distance from that of a last produced by the dependent grading movement.

10. In a last lathe, a model wheel, a cutter, 50 a swing mechanism, pantographic width grading mechanism and means for compounding with the movement of the swing mechanism caused by said grading mechanism, a movement independent of the dimensions of that part of the last being cut where- 55 by the surface of the last cut is placed at a uniform distance from that of a last produced by the pantographic mechanism alone.

11. In a last lathe, a model wheel and a cutter on a laterally fixed axis, mechanism 60 for presenting a model and a block to said wheel and cutter, said model wheel being constructed and arranged to cause a width grading motion of said mechanism.

12. In a last lathe, a combined model con- 65 tact guide and width grader having a fixed operative position, and arranged for variable curvature of its operative surface.

13. In a last lathe, a swing mechanism ar- 70 ranged to hold a model and a block, a cutter arranged to operate on said block, and mech- 75 anism for operating on said model to impart to said swing mechanism a copying and grading motion of amplitude differing by substantially a constant from proportion- ality to the radii of the model.

14. In a last lathe, a model wheel apparatus comprising a fixed hub and a plurality of interchangeable rims of progressively varying 80 effective surfaces.

15. In a last lathe, a cutter, and a com- 85 bined model wheel and grading apparatus comprising a hub and a plurality of inter- changeable rims of progressively varying diameters, the rims occupying correspond- 85 ingly progressively varying effective posi- tions relatively to the cutter.

16. In a last lathe, model and work hold- 90 ing mechanisms, a work contacting mecha- nism and a width grading mechanism com- prising a model wheel and connections con- 95 structed and arranged to grade the model perimeter by substantially an integral num- ber of sizes in width and to increase the length by substantially the same number of aliquot parts of a size in length.

17. In a last lathe, model and work hold- 100 ing mechanisms, model and work contacting mechanisms, means for pantographically re- producing the model longitudinally and means for non-pantographically increasing the length of the model by substantially $\frac{1}{4}$ size for each size increment in width.

18. In a machine of the class described, 105 model and work holding and treating mech- anisms, grading mechanism for pantograph- 110 ically reproducing the model in a plurality of dimensions, and means for non-pantograph- 110 ically increasing or decreasing the di- 115 mensions of the pantographic reproduction, the non-pantographic increase in length be- 115 ing substantially $\frac{1}{4}$ size for each size of non- pantographic increment in width.

In testimony whereof I have signed my name to this specification.

PAUL F. W. C. KRIPPENDORF.
